[57] CLAIM

The ornamental design for a faceplate for a module, as shown and described.

DESCRIPTION

FIG. 1 is an isometric view of a faceplate for a module showing our new design wherein a module is attached and shown in broken lines for illustrative purposes only and forms no part of the claimed design;

FIG. 2 is a front elevational view of the faceplate;

FIG. 3 is a back elevational view wherein the module is shown attached to the faceplate;

FIG. 4 is a left side elevational view of the faceplate;

FIG. 5 is a right side elevational view of the faceplate;

FIG. 6 is a top plan view of the faceplate; and,

FIG. 7 is a bottom plan view of the faceplate.
